UNITED STATES PATENT OFFICE.

WALTER P. MURPHY, OF CHICAGO, ILLINOIS, ASSIGNOR TO P. H. MURPHY COMPANY, OF PARNASSUS, PENNSYLVANIA, A CORPORATION OF PENNSYLVANIA.

CAR-ROOF.

1,238,428.

Specification of Letters Patent. Patented Aug. 28, 1917.

Application filed March 24, 1916. Serial No. 36,362.

To all whom it may concern:

Be it known that I, WALTER P. MURPHY, a citizen of the United States, and a resident of the city of Chicago, in the county of 5 Cook and State of Illinois, have invented a new and useful Improvement in Car-Roofs, of which the following is a specification.

This invention relates to heavy gage steel roofs intended primarily for freight cars, 10 but it is applicable to other kinds of roofs. The objects of the invention are simplicity, strength, durability, and tightness against leaks. A further object of the invention is the prevention of condensation of moisture 15 or "sweating" on the under sides of the roof plates.

This invention consists in the shape and arrangement of the carlines and roof plates and manner of securing them together. The 20 invention also consists in arranging a wood lining beneath the roof plates, and in the manner of assembling and retaining the lining in place. The invention also consists in the running board supports and manner of 25 securing them to the roof.

Further objects of the invention appear in connection with the following description of the car roof shown in the accompanying drawings, and what the invention consists 30 in is more particularly defined in the appended claims.

In the drawings, in which the same reference characters designate the same parts in the several views,

35 Figure 1 is a plan view of a portion of a car roof embodying the invention, parts of the top of the roof being removed to disclose the construction of the under part of the roof;

40 Fig. 2 is a transverse cross-section of the same on the line 2—2 in Fig. 1;

Fig. 3 is a similar transverse cross-section of the ridge portion of the roof, drawn to a larger scale than Fig. 2;

45 Fig. 4 is a longitudinal cross-section on the ridge line, showing the inside of the roof at the eaves and the under side of the roof in elevation;

Fig. 5 is a transverse cross-section of a 50 carline and portion of the roof adjacent thereto, on the line 5—5 in Fig. 1;

Fig. 6 is a transverse cross-section through

the eaves portion of the roof on the line 2—2 in Fig. 1; and

Fig. 7 is a longitudinal section through 55 the end of the car at the ridge, on the line 7—7 in Fig. 1.

The roof shown in the drawings is applied to a car having Z bar side plates 10 and a pressed metal end plate 11; but the invention is applicable to cars having wood side and end plates. The carlines 12 are of pressed steel, channel shape in cross-section, with the top edges of their side walls flanged outward for supporting the roof. 60 plates 13. The extremities of the carline flanges are depressed to form seats 14 for the ends of the lining boards 15. At the ridge of the car the depressed edges 14 of the carline flanges are cut away for a space 70 wide enough to permit the roof lining boards to be slipped into position on their seats beneath the roof plates. The ends of the carline flanges are bent down and hooked over and riveted to the inner flanges of the 75 side plates. End brackets 16 of pressed steel conforming to the shape of the under side of the carline at its ends are riveted to the side of the carline, and to the inner sides 80 of the side plates.

The side margins of the roof plates are lapped over the carlines, and are secured together and to the carline flanges by two rows of rivets 17. The rivets of each row pass through both roof plates and one of the 85 side flanges of the supporting carline between the trough portion thereof and the depressed edge 14 which forms a seat for the lining boards. The lapping portions of the roof plates and the carline together constitute a plate-carline of box-like shape having great vertical and lateral stiffness. The roof plates are spaced above the top edges of the side plates, and their eaves ends 18 are flanged down over the outer sides of the 95 side plates and are spaced a slight distance away from them. The downturned eaves flanges 18 of the roof sheets are secured to the side plates at their corners by rivets 19 which go through the ends of the carlines 100 and carline end brackets. The running boards 20 are bolted to angle iron cross pieces 21 which are supported at their ends by sheet metal brackets 22 which rest upon

the roof sheets over the carlines on each side of the ridge and are riveted to the carline flanges.

The invention is not restricted to the details of construction shown in the drawings.

I claim the following as my invention:

1. A metal car roof comprising trough shape carlines having outwardly projecting flanges along the tops of their side walls, roof plates supported on said carline flanges with their side margins lapping each other over the troughs of the carlines, and means for rigidly securing said lapping margins of said roof plates and said carline flanges together on both sides of the troughs to form a hollow plate-carline.
2. A car roof comprising trough shape carlines having outwardly projecting flanges along the tops of their side walls, the side edges of said flanges being depressed to form supports for lining boards, roof plates supported on the top portions of said carline flanges with their side margins lapping each other over the troughs of the carlines, lining boards arranged between said carlines with their ends between said roof plates and the depressed edges of said carline flanges, and means for rigidly securing said lapping margins of said roof plates and said carline flanges together on both sides of the troughs to secure said lining boards in place.

3. A metal car roof comprising side plates channel carlines having outwardly projecting flanges along the tops of their side walls, the ends of said carlines being bent down over the side plates, roof plates supported on said carlines with their side margins extending across the channels and each riveted to both flanges of each carline, said roof plates having their eaves ends turned down over the side plates, and means for rigidly securing said eaves ends of said roof plates and said carline flanges to said side plates.

4. A metal car roof comprising side plates channel carlines having outwardly projecting flanges along the tops of their side walls, the ends of said carlines being bent down over the side plates, roof plates supported on said carlines with their side margins extending across the channels and each riveted to both flanges of each carline, said roof plates having their eaves ends turned down over the side plates, and means for rigidly securing said eaves ends of said roof plates and said carline flanges to said side plates, said means including brackets embracing the under sides of said carlines and bearing against the inside of the side plates.

Signed at Chicago, Ill., this 21st day of March, 1916.

WALTER P. MURPHY.
